[57] CLAIM

The ornamental design for a battery charging adapter for a remote monitoring and alarm system, as shown and described.

DESCRIPTION

FIG. 1 is a top, front and left side perspective view of a battery charging adapter for a remote monitoring and alarm system showing my new design;

FIG. 2 is a right side elevational view thereof;

FIG. 3 is a top view thereof;

FIG. 4 is a left side elevational view thereof;

FIG. 5 is a bottom view thereof; and

FIG. 6 is a front elevational view thereof.
